UNITED STATES PATENT OFFICE.

WILLIAM J. BRITTING, OF WASHINGTON, DISTRICT OF COLUMBIA.

VERTICALLY-ADJUSTABLE SHADE-HANGER.

1,129,162.

Specification of Letters Patent. Patented Feb. 23, 1915.

Application filed July 10, 1914. Serial No. 850,166.

To all whom it may concern:

Be it known that I, WILLIAM J. BRITTING, a citizen of the United States, residing at Washington, in the District of Columbia, have invented certain new and useful Improvements in Vertically-Adjustable Shade-Hangers, of which the following is a specification.

This invention relates to shade hangers and more specifically to vertically-adjustable shade hangers.

The object of my invention is to provide a vertically adjustable shade hanger which will be simple in construction, durable, and efficient in operation.

An entirely new method of sliding adjustment is provided by means of the adoption of a ball-bearing slide, whereby the sticking tendency of adjustable shade hangers experienced with practically all other constructions, is entirely overcome. It is this tendency to stick which causes the shade, in other constructions, to get out of horizontal alinement and thus become inoperative. By my ball-bearing arrangement, the sliding is absolutely certain and sticking or catching impossible.

Furthermore, my invention also embodies a guide for the end of the shade, whereby the same is maintained in horizontal alinement, prevents the shade from rolling up unevenly, and also acts as a stop so that the shade will not wind up on the roller until the spring force is exhausted as so frequently happens with shade hangers as at present constructed.

Other objects of this invention not at this time more particularly enumerated, will be clearly understood from the detailed description and drawings forming a part of this specification.

Furthermore, this invention consists in the novel arrangement and combination of parts more particularly described in the following specification and embodied in the claims appended hereunto and forming a part of this application.

Referring now to the drawings which are merely illustrative of my invention, Figure 1 is a front elevation of my vertically-adjustable shade hanger in operative position upon a window. Fig. 2 is a cross-sectional view of one of the shade carriers taken on the line 2-2 of Fig. 1, while Fig. 3 is a front elevation of the opposite carrier show-

ing the operative position of the ball-bearings. Fig. 4 is a perspective of the pulley through which the adjustment cord passes. Fig. 5 is a cross-sectional view of shade guide and stop device taken on the line 5-5 of Fig. 1, while Fig. 6 is a detail perspective of the guide and stop member.

Referring further to the drawings, wherein similar reference characters indicate similar parts throughout the respective views, 1 designates a window casing, upon both sides of which is vertically mounted a guide member 2, best described as a rectangular sheet-metal tube, provided with a slot 3 along the longitudinal center through the outer face thereof. Shade hanger members 4 are adapted to be slidably mounted within said slot 3 and to be held in engagement in said tubular guide by means of ball-bearings 5 set into perforations 6 through said hangers 7 near the bottom thereof. Said bearings are arranged on both sides of said hangers in staggered relation to each other. The said perforations are in the form of a concavity and are of a diameter to receive so much of the balls only as will admit of contact by the balance of the ball with the side, top and bottom of the tubular guide member, thereby insuring perfect stability of the hanger as well as smooth and easy running 80 of the hangers to any position in the guides.

When it is desired to secure the guide members 2 to the front of a window casing fastening means are inserted through the bottom of said guide members, but when it is desired to secure them to the sides of a window casing a Z-shaped metal band 7 is clamped upon the outer portion of said guide member as shown in Fig. 5, and the free end thereof is secured upon the casing 95 at 8 by suitable fastening means.

The shade 18 is forced to roll up in vertical alinement by means of angle-iron slide members 9 secured upon both sides of the slat 19 at the end of the shade. The said slide member 9 is formed of a piece of sheet metal with one end thereof bent downwardly at right angles to portion 9a thereof, thus forming a foot portion 11 centrally disposed with respect to two lugs 12 which project 105 outwardly from said foot portion and at right angles thereto, said lugs being formed thereon at a certain point below the plane of portion 9a and above the terminal point of foot 11. In operative position, said foot 110

portion 11 rests upon the bottom of guide 2, while lugs 12 fit within the guide and slidably engage with the top thereof, being adapted to retain the slide within guide member 2 and also serving as a stop, when the curtain is rolled up, by reason of the contact of the lugs 12 with hangers 4. Portion 9^a of said slide member is provided with a longitudinal slot 10 therethrough, for ready adjustment upon the slat 19 so as to fit into the guide members 2; fastening means being inserted through said slot.

On both sides near the top of the window frame 1 and adjacent the upper ends of each 15 of the guides 2 is mounted a pulley 13. The wheel 13^a of said pulley 13 is inclosed on two sides 13^b and 13^c and one end 13^d thereof by a sheet-metal piece folded to so inclose said wheel; the opposite end being partially 20 inclosed by means of oppositely-arranged lugs 14 extending from the side 13^b to a certain point short of contact with the other side 13^c. This form of pulley is essential in order that the adjustment cord 15 may be 25 readily inserted between the ends of lugs 14 and the side 13^c to operative position upon the pulley wheel. The pulleys 13 are secured to the window frame by means of fastening members inserted through the perforations 13^e which are provided on opposite sides of the pulley wheel 13^a through the side 13^c of the pulley. Said pulley cords 15 are attached at 16 at one end thereof to hangers 4, the other ends of said cords being brought 30 up over the pulleys and down upon one side of the window frame with sufficient slack cord to be secured to a clip 17 whereby the shade is held in place at any point within the guides 2.

40 The utility, adaptability, and advantages of my improved form of vertically-adjustable shade hanger being obviously apparent, it is unnecessary to further enlarge upon the same herein.

45 Having now described and pointed out the new and useful features of my invention, I do not limit myself to the shape of certain parts where the shape is not essential, nor do I restrict myself to the exact details of 50 construction shown and described, but mean and intend to claim all equivalents and variations thereof not departing in principle from my invention and falling within the purview of the appended claims.

55 What I claim as my invention and desire to secure by Letters Patent is:

1. A device of the kind described comprising a substantially rectangular housing having a longitudinal slot in its outer face, one 60 of said housings adapted to be secured to each side of a window frame, a pulley mounted at the upper end of each of said housings, a hanger plate having openings at its forwardly projecting end adapted to receive a shade roller, said plate being pro-

vided with concave recesses in the side faces thereof, said plate being adapted to pass through said slot, ball-bearings adapted to seat in said recesses and be confined therein by frictional contact with the side walls of 70 said housing, and means for actuating said hanger plates.

2. A device of the kind described comprising a substantially rectangular housing having a longitudinal slot in its outer face, one 75 of said housings adapted to be secured to each side of a window frame, a pulley mounted at the upper end of each of said housings, a hanger plate having openings at its forwardly projecting end adapted to receive a shade roller, said plate being provided with concave recesses in the side faces thereof, said concave faces being located adjacent the inner edge of said plate, ball-bearings adapted to retain said plate within 80 said housing, and means for actuating said hanger plates.

3. A device of the kind described comprising a substantially rectangular housing having a longitudinal slot in its outer face, a 90 hanger plate having openings at its forwardly projecting end adapted to receive a shade roller, said plate being provided with concave recesses in the side faces thereof, said plate being adapted to slide within said 95 slot, ball-bearings adapted to seat in said recesses and be confined therein by frictional contact with the side walls of said housing, and means for actuating said hanger plate.

4. A device of the kind described comprising a substantially rectangular housing having a longitudinal slot in its outer face, one 100 of said housings adapted to be secured to each side of a window frame, a pulley mounted at the upper end of each of said 105 housings, a recessed hanger plate having means at one end adapted to receive a shade roller and the other end thereof adapted to enter said slot, removable antifriction means adapted to enter said housing and retain 110 said plate within said slot, and means for actuating said plate.

5. A device of the kind described comprising a substantially rectangular housing having a longitudinal slot in its outer face, one 115 of said housings adapted to be secured to each side of a window frame, a pulley mounted at the upper end of each of said housings, a hanger plate provided with concave recesses in the side faces thereof, said 120 recesses formed on both sides of said plate in staggered relation with respect to each other and adjacent the inner edge of said plate, ball-bearings adapted to seat in said recesses and be confined therein by frictional 125 contact with the side walls of said housing, and means for actuating said plate.

6. A device of the kind described comprising a substantially rectangular housing having a longitudinal slot in its outer face, a 130

hanger plate having openings at its forwardly projecting end adapted to receive a shade roller, said plate being provided with concave recesses in the side faces thereof, 5 said plate being adapted to slide within said slot, ball-bearings adapted to seat in said recesses and be confined therein by frictional contact with the side walls of said housing, means for actuating said hanger plate, a 10 shade secured to said shade roller, and means adapted to maintain the end of said shade in horizontal alinement.

7. A device of the kind described comprising a substantially rectangular housing having a longitudinal slot in its outer face, a hanger plate having openings at its forwardly projecting end adapted to receive a shade roller, said plate being provided with concave recesses in the side faces thereof, 15 said plate being adapted to slide within said slot, ball-bearings adapted to seat in said recesses and be confined therein by frictional contact with the side walls of said housing, means for actuating said hanger plate, a 20 shade secured to said shade roller, and means secured at the end and on both sides of said shade adapted to fit within said hanger 25

whereby the end of the curtain will be maintained in horizontal alinement.

8. A device of the kind described comprising a shade roller, a shade secured to said roller, a guide member formed of a metallic strip adjustably secured upon both sides at the end of said shade, said guide member having a body portion and a lug formed 30 upon the free end thereof at right angles to said body portion, oppositely disposed lugs on both sides of said last named lug slightly beneath the plane of said body portion and projecting forwardly in parallelism with respect to said body portion, said body portion provided with a longitudinal slot therethrough adapted to receive a securing element, and a substantially rectangular housing adapted to receive the free end of said 35 guide member, and a ball bearing hanger adapted to slide within said housing and carry said shade roller.

In testimony whereof I affix my signature in presence of two witnesses.
